CENTRIFUGAL BASKET CONSTRUCTION

Eugene Roberts, Hastings, N. Y., assignor to The
Western States Machine Company, Salt Lake
City, Utah, a corporation of Utah

Application February 25, 1933, Serial No. 658,544

REISSUED

4 Claims. (Cl. 210—76)

This invention relates to baskets for centrifugal separators of the type used in the manufacture of sugar, starch and various chemicals and is intended to provide a construction of basket 5 that shall be free from faults inherent in the type of construction that has previously been known and used in such centrifugals.

According to the practice heretofore followed 10 a perforated metallic sheet of appropriate length and thickness was rolled into cylindrical form and its abutting edges were fastened together by means of butt straps. The perforations in the sheet extended close to the top and bottom edges and were arranged in circumferential perforated 15 areas separated by intermediate circumferential areas that were left imperforate for the reception of external reenforcing hoops. Said abutting ends were fastened together by a series of vertically spaced butt straps which were curved 20 strips of sheet material as thick, or thicker than the basket wall overlapping the perforated areas for several inches on each side of the joint or crack in the basket wall. These straps were secured to the wall by multiple rivets passed 25 through perforations in their ends that were in registry with corresponding perforations in the basket wall. To balance the basket, it was necessary to apply two additional sets of similar straps 120 degrees from the butt straps and fastened to the basket also by rivets.

The top and bottom elements of the basket were then applied to the corresponding edges of the basket wall in lapped relation thereto and were fastened to it by bolts, pins or rivets. The 30 reenforcing hoops passed between the individual straps of each row of butt straps.

For many years the baskets in use have been 35 of this type of construction, although it was recognized that their operation in service was attended by a very considerable waste of material being treated. Not only were the baskets subject to leakage around the top and bottom edges of their filter linings, but unless the sugar being centrifuged was subjected to excessive application of wash water there would be found rings and patches of discolored sugar due to imperfect purging and washing. Now, it is well known that each pound of wash water sprayed against the sugar wall, after purging, carries off in solution about three and one-half pounds of sugar, if cold water be used. If hot water be used (numerous refiners prefer it because it more quickly picks up the scum) the loss of sugar averages seven pounds for each pound of hot water applied. Moreover, imperfect drainage prolongs

the purging period, that is, the centrifugal extraction of the original syrup or liquor with which the grains were mixed, and makes the washing operation longer and more difficult.

After careful study of and experiment with 5 centrifugals in attempting to learn the causes of these troubles, I have discovered that the large percentage of waste involved in the operation of such centrifugal baskets was due to several faulty features of construction, whose disadvantages have been entirely overlooked heretofore. The importance of uniform drainage throughout the whole perforated area of the basket wall has not been appreciated or, if it has been, no basket construction has been provided to secure 10 that advantage. In the first place, the use of butt straps and counterbalance straps, as well as the use of overlapping flanges forming top and bottom riveted joint connections with the basket wall, has resulted in doubling the thickness of 15 the basket wall at such locations with the consequence that the depth or radial length of the outlet perforations in the double thickness areas was also doubled. Careful tests have shown me that these longer outlet perforations tend to gum 20 up or accumulate sticky material until their discharge capacity is very greatly reduced. In addition to this, some of the holes are closed by the attaching rivets. Therefore, substantial 25 areas of the basket wall will have less than half 30 the freedom of drainage that equal areas in other parts of the basket have. The result is that after purging and moderate washing there will be found discolored streaks and patches of sugar, which are highly objectionable as such 35 sugar is of inferior grade. On the other hand, if these discolored areas are washed out by sufficient washing the portions of the sugar wall having freer drainage become excessively 40 washed, involving excessive wastage, which is 45 also highly uneconomical and objectionable.

By means of the construction hereinafter described I have eliminated perforated areas of double thickness of basket wall and have also eliminated the use of fastening rivets which have been used for fastening overlapped perforated members together and which necessarily close a considerable number of such perforations and have thereby secured, for the first time in this art, a perforated centrifugal basket for sugar 50 centrifugals and the like, which have uniformly spaced outlet perforations of uniform depth or radial length so that all portions of the perforated area of the basket wall possess equal drainage facilities, thereby avoiding the occurrence 55

- of dark or discolored areas of sugar and at the same time using a markedly decreased application of wash water, largely reducing previous wastage. Moreover, by reason of the equal and free drainage thus secured, the purging can be accomplished more perfectly and more quickly than before, which of itself aids in dispensing with the use of considerable quantities of wash water, since much of the scum is carried off by the freely flowing liquor or syrup extracted in the first portion of the run before the wash spray is applied.
- Waste of material through leakage around the top and bottom edges of the basket filter linings is avoided by spacing the top and bottom rows of perforations a substantial distance from the top and bottom elements, thereby providing a smooth unbroken surface of sufficient extent to form an adequate support for the selvage edged linings with which these smooth unbroken top and bottom margins or selvage areas of the basket wall form an effective seal permitting the use of linings that are slightly shorter in vertical height than the vertical distance between the top and bottom elements next to the basket wall. Besides providing a perfect sealing seat for the top and bottom edges of the lining, these smooth unbroken selvage areas serve to prolong the life of the fine linings, since in being crowded tightly against the top and bottom in the effort to prevent leakage of material at those points they become bent and crumpled at their edges under pressure exerted by the discharger plow, which is a prolific source of damage to the linings. Moreover, the selvage margin areas of the basket wall afford a much stronger and more reliable joint with the top and bottom elements of the basket than was obtained by previous constructions.
- These and other features of the invention will be particularly described in the following specification and will be defined in the claims hereto annexed.

In the accompanying drawing I have illustrated a preferred form embodying the principles of this invention, in which

Fig. 1 is a side elevation, partly in central section, of my improved basket construction showing the basket in its relation to the surrounding curb or casing.

Fig. 2 is a detail showing in perspective on a larger scale the joint between the bottom and the basket wall and illustrating the calibration of the bottom for the purpose of ascertaining the thickness of the sugar wall as the basket is being loaded.

Fig. 3 is an enlarged detail showing a vertical section through the upper portion of the basket wall and top.

Fig. 3^a is a detail showing in elevation on the same scale as Fig. 3 the arrangement of perforations of the basket wall.

Fig. 4 is an enlarged detail in plan of the abutting ends of the sheet forming the peripheral wall with their uniting welding seam indicated.

In the practice of this invention I avoid double thickness of the perforated area of the basket wall by elimination of the butt straps and counterbalance straps and of overlapping joints having outlet perforations by making the basket of completely integral construction, thereby securing uniform depth of the outlet perforations and uniform distribution or spacing of such perforations throughout the perforated area of the basket, so that equal and rapid drainage is af-

firmed to all portions of the perforated area of the basket while at the same time I provide a lighter and a stronger and more reliable basket construction.

I will now describe in detail the features of construction and arrangement by which these important advantages are secured. The suspension shaft 1 of the centrifugal, according to usual practice, is provided at its lower end with a frusto-conical enlargement 2 and a downward extension 2^a of reduced diameter for the purpose of receiving the hub 6 concentric with the radial arm spider 5, which sets over the bottom extension 2^a and is fastened thereto by bolts tapped into the enlarged head 2 of the spindle. 10

I provide a novel construction of spider for the basket bottom by thickening the interior hub member 6 of the spider and the peripheral ring 7 of the spider and by reason of this extra thickness at these two points of greatest strain I am 20 able to shorten the vertical depth of the peripheral ring 7 sufficiently to allow this ring, when the basket gyrates, to swing over the top of the interior flange 20^b bounding the central discharge opening in the bottom 20^a of the curb or casing. 25 This upward inclination of the spider 5, with the corresponding thickening of the hub and peripheral ring thereof, makes it possible to provide a collecting trough or ring for the bottom of the curb or casing of much greater width than was 30 practicable with previous constructions in this type of centrifugal without sacrifice of strength.

The perforated basket wall 10 comprises a metallic sheet provided with uniformly spaced and dimensioned perforations throughout the whole 35 perforated area of the basket, while at the same time providing at the top and bottom marginal portions of the basket wall selvages or imperforate areas 10^b and 10^c for the reception of my selvage edge lining or backing, which forms the 40 subject matter of a companion application, and prevents leakage of the material around the linings at the top and bottom edges thereof. Not only is the pitch or center to center distance from one perforation to the next in the same 45 row of perforations the same, but the pitch or distance from center to center of successive rows of perforations is also uniform throughout and in consequence thereof there is uniform and equal drainage throughout the basket for the escape of 50 the centrifugally extracted liquid. Furthermore, the radial depth of all perforations in the basket is uniform throughout, since there are no rows of butt straps secured to the basket wall and no rivets plugging a substantial number of the 55 perforations by reason of the construction that will now be explained.

The perforated sheet is rolled into cylindrical form and its opposing ends are cut off true and even and bevelled at their edges, and are then 60 drawn tightly together by circumferential clamps provided with draw bolts. These abutting ends of the sheet 10, while the shell is held in cylindrical form, are then welded together throughout the length of the seam from top to bottom, thus 65 making an integral connection between the two ends. The inside and the outside surfaces of the welded seam are then ground smooth.

The top and bottom edges of the integral cylindrical sheet to form the basket wall are then 70 turned to form a snug fit with the top and bottom elements of the basket; the bottom is then forced into the inside of the bottom edge until its outer edge lies flush with the bottom edge of the shell; the top ring 12 is then crowded over 75

the top edge against intervening vertical spacers and the top and bottom are then drawn together against the intervening spacers to secure exact parallelism as well as proper engagement with the edges of the basket wall. When thus exactly positioned with reference to each other and to the basket wall, the top and bottom elements are exactly equi-distant from each other all around the basket and a continuous welded seam is made between the bottom and top elements while they are held in that relation. In the case of a steel basket, the continuous welded seat at top and bottom will preferably be formed by arc welding. In case of bronze or similar alloys the welding is preferably done by oxy acetylene method of welding.

The hoops 13 are turned or machined inside to slightly smaller dimension than the periphery of the basket wall and are then heated and forced over the basket wall in proper spaced relationship insured by temporary spacers. These hoops are shrunk tightly on the basket wall by cooling and are held against accidental displacement by spot welding at intervals around the basket wall, as shown at 13^a, such spot welding preferably being made alternately on the top and bottom sides of the hoops. The bottom hoop is the last to be applied and after its application is integrally welded to the bottom marginal portion of the basket wall by a continuous welding seam extending entirely around the bottom. As the basket bottom has already been integrally united with the inside face of the lower edge portion of the basket wall by a continuous welding seam, as above explained, this continuous welding of the bottom hoop forms, in effect, a peripheral integral extension of the bottom member and therefore the shocks, caused by its impact against the surrounding wall of the curb or casing as the basket gyrates or sways, are transmitted directly to the basket spindle and there is no danger of the hoop becoming loosened and dropping off, which occasionally happens with consequent damage to the basket when the hoop is secured in place only by pins.

By the above described method of construction applicant has produced a centrifugal basket of integral construction which is not only superior in strength but which effects a much more complete and satisfactory drainage than in the case of previous constructions, and also makes provision for the elimination of leakage of material to be purged around the top and bottom edges and permitting the use of a collecting trough for the liquid of any desired width instead of being restricted to the narrow widths heretofore necessitated by previous constructions. There are no rivets to shear or to clog drainage openings and no butt straps to impair complete efficiency of drainage.

The outer portion 8 of the basket bottom 4 is provided with a series of accurately spaced gauging grooves or rings 4^a so that the centrifugal operator or attendant is guided accurately in loading the basket. These calibrating or gauging rings 4^a will preferably be located an inch apart, the outer one of these being one inch, or unit of measurement, from the inside of the basket wall, so that if it is known that the inner ring of any given basket, for example, is 7 inches away from the basket wall and it is desired to load some particular material into the basket to a thickness of only 5 inches, the operator will know when the material has built out to the third ring, counting from the inside, before it is necessary to stop

inches and correspondingly any other desired thickness may be indicated by similar manner, thus enabling the operator to load to any desired thickness of wall according to the material that is being purged. A further important advantage of the visible calibrating of the basket bottom is that it makes possible the accurate ascertainment of the amount of shrinkage in the thickness of the bottom portion of the sugar wall, thereby affording a check on excessive washing or leakage of material. When the material being centrifuged is loaded into the basket it builds up into a vertical annular wall inside of the outside wall of the basket and normally this walled up ring of material is thicker at the bottom than at the middle and top portions and therefore should receive a slightly greater supply of wash fluid than the upper portions of the walled up ring receive. Therefore, by providing a calibrating means on the bottom the shrinkage can be checked up for the purpose of determining precisely how much more spraying is required over this area and also to detect the fact of over-spraying which will cause excessive shrinkage and consequent waste.

In actual practice I have made the imperforate marginal portions 10^b and 10^c of the perforated basket wall at top and bottom approximately one-half inch in width, or a little wider than the diameter of the outlet perforations, although this dimension is not prescriptive. These smooth marginal or selvage areas of the basket wall afford a smooth uninterrupted annular seat at top and bottom forming a continuous sealing support for the upper and lower selvage edges of the basket filter linings. This is important because baskets, as previously constructed with the top and bottom rows of outlet perforations very close to the top and bottom elements of the basket, I have found are a prolific source of leakage of material at these points. Furthermore, in the attempt to lessen leakage it has been customary to endeavor to fit the finely perforated filter linings snugly between the top and bottom walls with the result that this fine lining has become curled up or distorted under the pressure of the discharger plow so that leakage of material at both top and bottom occurs. When the above described marginal selvages are used, it is unnecessary to have the finely perforated filter lining fit snugly between the top and bottom of the basket and the same may be made slightly shorter than the vertical distance between top and bottom to allow for expansion and as the sealing at top and bottom is effected by the smooth contact of the selvage portion of the outer lining or backing with these smooth selvage areas of the basket wall, leakage is prevented and the life or duration of the fine filter linings is very greatly prolonged, thus reducing the cost of maintenance of the centrifugals in operation. To get the fullest advantage of these imperforate selvage areas I have devised an improved basket lining having top and bottom sealing selvages, but such improved lining forms the subject matter of another copending application filed by me.

By shortening the outer ring of the bottom spider with compensating thickening of the ring, new baskets of this construction may be mounted in wide trough casings without narrowing the diameter of the spider and without changing the vertical depth of the basket, while at the same time avoiding the objectionable impact of the outside ring of the spider with the gauge ring of the trough when the basket is suspended from the rear of the

the collecting trough of the curb to an undesirable extent.

What I claim is:

- 5 1. A centrifugal basket of the type described comprising appropriate top and bottom members and a perforated peripheral wall integrally united therewith, said wall comprising a heavy metallic sheet bent into cylindrical form with its abutting end edges integrally welded together 10 and having uniformly spaced outlet openings, all of which are of equal radial depth throughout whereby equal and uniform drainage is afforded for the escape of the centrifugally extracted liquid from the walled up material in 15 the basket.
- 20 2. A centrifugal basket of the type described comprising a perforated peripheral wall of uniform thickness throughout, thereby providing outlet perforations of uniform depth radially of the basket, and top and bottom elements united therewith, the top and bottom rows of perforations being spaced a substantial distance from said top and bottom elements to leave a smooth unbroken annular selvage area of adequate width 25 to form a smooth sealing contact with the sub-

tending sealing selvages of an inserted basket lining, thus preventing leakage of material around the top and bottom edges of the lining.

3. A centrifugal basket comprising a perforated sheet of annular form having its opposite end edges welded together in abutting relation, thereby providing a perforated wall of uniform thickness having outlet perforations of equal radial depth throughout, and top and bottom elements of appropriate form united to the top and bottom edge portions of said wall.

4. A centrifugal basket of the perforated wall type embracing a perforated cylindrical basket wall of uniform thickness throughout, comprising a metallic sheet bent into cylindrical form 15 with its end edges integrally united in abutting relationship, thereby providing outlet perforations of equal depth uniformly spaced apart, top and bottom elements united thereto by continuous welding seams, and a series of vertically 20 spaced external reinforcing hoops secured around the basket wall and held in fixed spaced relationship to each other by spot welding.
